Attorney

UNITED STATES PATENT OFFICE

ERNESTO JOSE POMMER, OF MORON, ARGENTINA

AUTOMOBILE RADIATOR

Application filed September 19, 1932. Serial No. 633 930.

My invention relates to improvements in a device for cooling engines, and is more particularly adapted to be used in connection with internal combustion engines which are 5 inclined to overheat and, consequently, necessitate a frequent filling of the radiator connected therewith.

The invention may be mounted in the position easily accessible to the driver of the 10 vehicle and capable of receiving hot water from the radiator, if so desired, or supplying, or replenishing a quantity of cooler water in its place. It is not necessary to use the device continuously, but only at such 15 times as the engine becomes overheated or replenishing the necessary water to preserve the proper amount of water in the radiator.

The objects of the invention are as follows:

First, to provide an attachment to a radiator of the class indicated which will omit the 20 usual visual filling opening and cap on the top of the old form of radiator, thereby eliminating all possibility of the expensive and usual form of radiator caps being surreptitiously removed or stolen, and at the same 25 time provide a clear field of vision for the driver from his seat over the radiator.

Second, to provide a construction of radiator attachment in which the radiator filling 30 opening is under the hood of the car, thereby preventing any of the water, steam or vapor of the alcohol from passing out of the radiator, over the hood and against the windshield and into the body of the car while under way, 35 and at the same time making for simple construction and reducing the air resistance and effecting nearer the stream line contour which the modern car manufacturers are desirous of carrying out.

Third, to provide a construction of a radiator attachment which is capable of being manufactured and applied on all existing and common forms of radiators at a minimum of 40 cost without disturbing any of the originally installed positions of the radiator, engine hood or instrument board.

Fourth, to provide a construction of radiator and reserve water container in which the 45 levels of the water in the radiator and reserve water container are always visible and the

reserve water can be quickly and easily conveyed to the radiator with the least effort.

Fifth, to provide a construction of radiator 55 in which the usual radiator cap is omitted and the filling opening is provided with a flexible, collapsible and extensible pipe through which the water can be conveyed into the radiator without spilling any of the water on said radiator or engine casting.

Sixth, other objects and advantages of the 60 invention will appear from the detailed description of the construction and arrangement of the several elements of the invention and manner of their cooperation and using 65 the same.

The invention consists of structural characteristics and relative arrangements of elements which will be hereinafter more fully described and particularly pointed out in the 70 appended claims.

In the drawing, in which similar reference characters indicate the same parts in the several figures:

Figure 1 is a fragmentary side elevation, 75 partly in section of the invention as applied to an internal combustion engine;

Figure 2 is a top plan view of the invention when the hood of the engine is removed;

Figure 3 is an enlarged sectional view of 80 the filling opening of the radiator and attachments thereto; and,

Figure 4 is an enlarged sectional view of 85 the water level tubes taken on the line IV—IV of Figure 1.

Referring to the drawing, 10 is the upper or cylinder section of the usual internal combustion engine provided with the usual circulatory water inlet 11 and outlet 12, as indicated. 13 is the radiator having its bottom section or opening 14, connected by means of conduit or tube 15 with the water inlet 11 of the engine. The top 16 of the outer section of the radiator is closed and is flush with the usual form of hood 17, shown in dotted lines, said radiator being provided with the common form of overflow pipe 18 which has its upper end 19 within and near the upper portion of the top 16 of the radiator 13, while its lower end extends outside 95 of the bottom section 14 of radiator 13, as is 100

the approved practice and needs no further disclosure.

The interior of the upper or top portion 16 of the radiator is preferably provided with 5 and connected with a hollow section or casing 21, which forms an enlargement or rear-ward extension of the space at the top and interior of the radiator and which projects towards the engine and is below and under 10 the hood 17 when said hood is in its normal or closed position, as indicated.

The lower portion of the hollow section 21 is in communication by means of a tubing or conduit 22 with a water outlet 12 of the 15 engine 10, as clearly illustrated. The upper portion of the casing 21 is provided with a filling opening 23 having an upwardly ex- 20 tending flange 24 to which is suitably secured one end of the flexible and collapsible hose or tubing 25, as clearly shown in Figure 3. The free end of said tubing 25 is provided or securely attached to a funnel-shaped ring 26 to permit water to be easily 25 poured into the tubing 25, when extended, and through the opening 23 to be received by the hollow section 21 and radiator 13.

27 is an outwardly flaring annular mem- 30 ber, which is attached to the top of the hol- low section 21 and over the opening 23 and surrounds the flange 24, said member 27 forming a receiving pocket and storage chamber for the funnel-shaped ring 26 and the connected tubing 25, when said tubing is in its collapsed position, as shown in Figure 3.

35 28 is a reserve water chamber or tank connected to the lower portion of the hollow section 21 by means of a tube or conduit 29 controlled by the valve 30, whereby any water in said reserve tank 28 may be permitted to 40 flow through the casing 21 and into the radiator 13, for purposes to be presently de- scribed.

31 is a vent opening to permit air to enter 45 into the reserve tank 28, while 32 is a valved outlet at the lower portion of said tank 28 for purposes of draining the same or enabling one to secure water for such purposes as found necessary.

50 33 represents a section of the instrument board of an automobile to which is suitably attached two independent upright water gauge tubes 34 and 35, see Figure 4, so ar- ranged as to be visible by the driver of the car. The upper and lower ends of the tube 55 34 are connected to the upper and lower portions of the casing or hollow section 21, re- spectively, by the tubes 36 and 37, while the upper and lower ends of the tube 35 are con- 60 nected to the upper and lower portions of the reserve tank 28 by tubes 38 and 39, re- spectively, as indicated in Figures 2 and 4. The open ends of the tubes 34 and 35 are se- 65 curely held with water tight connections over the openings 40 and 41 in tubes 36 and 37 and

38 and 39 by means of properly shaped upper and lower bridge pieces 42 and 43, which are drawn towards each other by a long bolt 44 provided with a winged nut 45, after a series of washers or gaskets 46 are inter- 70 posed between the ends of the tubes 34 and 35 and ends of tubes 36, 37, 38 and 39, as clearly shown in Figure 4 and needs no further disclosure.

The manner of using the invention is as 75 follows:

Should it be found by the indication of 80 gauges 34 and 35 that it is necessary to fill the radiator 13 and reserve tank 28 with wa- 85 ter, the hood 17 is raised and the valve 32 of the tank is closed, and the valve 30 controlling the communication through pipe 29 be- 90 tween said radiator 13 and tank 28 is opened.

The flexible and collapsible pipe 25 is then 95 extended and its attached funnel 26 is held above and to the side of the radiator 13 and engine 10. Water is then poured into the said funnel 26 and permitted to gravitate down 100 said extended pipe 25 into the hollow exten- 90 sion or section 21 and from there flow into the radiator 13 and reserve tank 28.

After sufficient water, as indicated by 105 gauges 34 and 35, has been supplied to the radiator 13 and tank 28, the valve 30 is closed 95 thereby cutting off the reserve water supply 110 from the radiator. The collapsible pipe 25 with its funnel 26 is returned to storage chamber or pocket formed by the attached flaring member 27, so as to assume the position 115 shown in Figure 3, when the collapsed and repeatedly folded sections of the pipe 25 will tightly close up the interior of said pipe 25, and seal up the passage therein and prevent any water from escaping through 120 the opening 23. The hood 17 is then returned 105 to its normal position, as indicated in Figure 1, and, as will be seen, no outer obstruc- 110 tions or radiator cap is seen attached to the top of the radiator, nor will the reserve water tank with its connections and valves be ca- 115 pable of being tampered with or stolen.

When the driver notices by observation of 125 the gauge 34 that the water level in the radia- tor is approaching a low level, it is only neces- sary to open the valve 30 and replenish the same to the desired level and again close 130 said valve 30. Should the water in reserve tank 28 need to be replenished according to 120 observation of gauge 35, the same may be supplied through vent 31, but preferably 130 through the opening 23, by repeating the operations just described.

From the foregoing description of the con- 125 struction and arrangement of the elements and manner of using the improved device, it will be seen that all the objects and advan- 130 tages recited in the statement of invention have been fully and efficiently carried out, and many changes will readily suggest them- 135 selves to any one without departing from the

spirit of the present invention or scope of the claims.

Having thus ascertained the nature of my invention, what I claim as new and desire to 5 protect by Letters Patent, is:

1. The combination with a motor vehicle engine, a radiator with a closed top and a lateral hollow extension below the top of and communicating with said radiator and projecting towards and communicating with the cooling jacket of said engine and provided with a filling opening on its upper side below the hood, a reserve tank on the same level with said lateral hollow extension and 10 having communication therewith, and means to cut off said communication between said hollow extension and reserve tank.

2. The combination with a motor vehicle engine, a radiator with a closed top and a lateral hollow extension below the top of and communicating with said radiator and projecting towards and communicating with the cooling jacket of said engine and provided with a filling opening on its upper side below 15 the hood, a reserve tank on the same level with said lateral hollow extension and below the top of the radiator and having communication with said extension, and means to cut off said communication between said hollow extension and reserve tank.

25

3. The combination with a motor vehicle engine, a radiator with a closed top and a lateral hollow extension below the top of and communicating with said radiator and projecting towards and communicating with the cooling jacket of said engine and provided with a filling opening on its upper side below the hood, a reserve tank on the same level with said lateral hollow extension and 30 having communication therewith, means to cut off said communication between said hollow extension and reserve tank, said lateral hollow extension having a gauge for indicating the level of a fluid in said radiator and 35 hollow extension.

4. The combination with a motor vehicle engine, a radiator with a closed top and a lateral hollow extension below the top of and communicating with said radiator and projecting towards and communicating with the cooling jacket of said engine and provided with a filling opening on its upper side under the hood, a reserve tank on the same level with said lateral hollow extension and having communication therewith, means to cut off said communication between said hollow extension and reserve tank, each of said lateral hollow extension and reserve tank having 50 an independent gauge for indicating the levels of the fluid in the same.

5. The combination with a motor vehicle engine, a radiator with a closed top and a lateral hollow extension below the top of and communicating with the cooling jacket of said engine and provided with a filling opening 55

on its upper side below the hood, a flexible and collapsible conduit connected to said filling opening below the hood, a reserve tank on the same level with said lateral hollow extension and having communication therewith and means to cut off said communication between said hollow extension and reserve tank.

6. The combination with a motor vehicle engine, a radiator with a closed top and a lateral hollow extension below the top of and communicating with said radiator and projecting towards and communicating with the cooling jacket of said engine and provided with a filling opening on its upper side below the hood, a reserve tank on the same level with said lateral hollow extension and below the top of the radiator and having communication with said extension, means to cut off said communication between said hollow extension and reserve tank, each of said hollow extension and reserve tank having an independent gauge for indicating the levels of the fluid in the same.

7. The combination with a motor vehicle engine, a radiator with a closed top and a lateral hollow extension below the top of and communicating with said radiator and projecting towards and communicating with the cooling jacket of said engine and provided with a filling opening on its upper side below the hood, surrounded by a storage chamber, a flexible and collapsible conduit connected to said opening adapted to be deposited in said storage chamber, a reserve tank on the same level with said lateral hollow extension and having communication therewith, and means to cut off said communication between said hollow extension and reserve tank.

In testimony whereof, I affix my signature.

ERNESTO JOSE POMMER.
